(57) **CLAIM**

The ornamental design for a cordless ratchet, as shown and described.

DESCRIPTION

FIG. 1 is an enlarged back view of the cordless ratchet of the present invention.

FIG. 2 is a right side view of the cordless ratchet of FIG. 1.

FIG. 3 is a top view of the cordless ratchet of FIG. 1.

FIG. 4 is a left side view of the cordless ratchet of FIG. 1.

FIG. 5 is a bottom view of the cordless ratchet of FIG. 1.

FIG. 6 is an enlarged front view of the cordless ratchet of FIG. 1; and,

FIG. 7 is top right-side perspective view of the cordless ratchet of FIG. 1.

The broken lines illustrate portions of the cordless ratchet which form no part of the claimed design.
